CLAIM

The ornamental design for a pet water fountain, as shown and described.

DESCRIPTION

FIG. 1 is a front elevational view of a pet water fountain showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a third perspective view thereof;

FIG. 10 is a first perspective view of portion A of FIG. 9;

FIG. 11 is a second perspective view of portion A of FIG. 9; and,

FIG. 12 is a third perspective view of portion A of FIG. 9. The broken lines in the drawings illustrate portions of the pet water fountain which form no part of the claimed design.

1 Claim, 12 Drawing Sheets
